CORDLESS MUSCLE STIMULATOR

Kenneth R. Leverenz, Brookfield, Ill., and George H. Stafford, P.O. Box 5187, Santa Monica, Calif. 90405; said Leverenz assignor to said Stafford

Filed Sept. 18, 1967, Ser. No. 8,621

Term of patent 14 years

(Cl. D83—1)

FIG. 1.

FIG. 2.

FIG. 4.

FIG. 3.

FIG. 5.

FIG. 6.

FIG. 7.

FIG. 1 is an isometric view of a cordless muscle stimulator embodying our new design;

FIG. 2 is a top plan view of the same;

FIG. 3 is a bottom plan view;

FIG. 4 is an elevational view of one end;

FIG. 5 is an elevational view of the other end;

FIG. 6 is an elevational view of one side;

FIG. 7 is an elevational view of the other side.

We claim:

The ornamental design for a cordless muscle stimulator, substantially as shown.
